UNITED STATES PATENT OFFICE

JOSEPH P. FOUKES, OF PITTSBURGH, PENNSYLVANIA, ASSIGNOR TO LEE C. MOORE & COMPANY, INCORPORATED, OF PITTSBURGH, PENNSYLVANIA, A CORPORATION OF PENNSYLVANIA

REINFORCING LEG AND CLAMP FOR ANGLE-IRON DERRICKS

Application filed September 27, 1926. Serial No. 137,862.

This invention relates to all-metal derricks or towers for oil well drilling rigs, and the like. More particularly it relates to such derricks having permanent legs or corner columns of angle bar sections adapted to be combined with temporary reenforcing legs composed of angle bar sections for making the derrick strong for drilling purposes, the temporary legs being removed after drilling 10 is completed, leaving a light permanent derrick for pumping purposes. More particularly still the invention relates to the means for attaching temporary legs to the permanent legs of such towers or derricks.

An object of the invention is to provide positive means for attaching a temporary angle bar derrick leg to a permanent angle bar derrick leg in such manner that the two will be held rigidly together at points sufficiently 20 close to make them in effective strength a single leg. Another object is to provide such means in a form that may be readily and easily attached and detached without special tools and without weakening the permanent 25 structure, of a very simple form, with a minimum number of movable elements such as bolts, economical to manufacture, easy to handle, and of minimum weight.

Referring to the drawings, Fig. 1 is a partial side elevation showing the permanent and reenforcing derrick legs in associated position, with the usual girts and braces attached to the permanent leg; Fig. 2 is a horizontal section on the line II-II of Fig. 1; 35 and Fig. 3 is a horizontal section on the line III-III of Fig. 1.

All metal derricks for oil wells and the like, comprising corner leg columns composed of angle sections abutting end to end and attached together and to girts and braces by suitable means are already well known. In 40 Fig. 1 a part of a standard form of such a derrick structure is illustrated, the permanent leg sections being marked A, and a temporary reenforcing leg associated therewith by the 45 clamps constituting this invention being marked B.

The permanent legs are made up of the section A, angle bars the two legs or sides of 50 which are respectively marked 1 and 2. The

temporary or reenforcing derrick legs or columns are made up of section B, preferably of twice the length of section A, the two legs or sides of the angle sections B being marked respectively 3 and 4.

The permanent legs are made up of the sections A attached together by splice bars 5 positioned on each side of the adjoining legs of the sections at the point where they are abutted together, with bolts extending 60 through the splice bars and the legs of the angle iron sections. Diagonal braces 6 and horizontal girts 7 are attached in a manner well known in this art, and not peculiar to this invention. The structure of such derricks generally being well known.

The removable reenforcing legs made up of angle sections B are positioned outside the permanent legs made up of angle section A, with the apices or backs of the two angle columns in juxtaposition, so that the legs of the section A and the legs of the section B extend in opposite direction, but in the same planes. The permanent angle columns have their apices or backs out, with their sides in the planes of the sides of the derrick as a whole. The reenforcing angle columns have their backs inward, with their sides extending outward also in the planes of the sides of the derrick structure as a whole. This forms in 70 effect a two-piece column with sides extending in four directions at right angles. The description just given is on the supposition that right angle bars will be used. That is the usual practice. If bars of different angularity are used the general arrangement would be similar, but the sides would not lie at right angles or in the planes of the sides of the derrick.

The temporary reenforcing sections B are 75 rigidly attached to the permanent sections A by means of angle bar clamps or brackets C and C'. These consist of angle shaped brackets having one straight side, the other side having a terminal outwardly turned hook adapted to extend over and around the edge of one of the legs of the permanent sections A, used in the derrick construction that is to be left up. The other leg 8 of the bracket 80 or clamp is perforated, so that a bolt 11 or

100

12 may extend through it and through one of the legs of the reenforcing angle section B, all as illustrated in Fig. 3.

These clamps are shaped so that they will fit accurately within the angle formed by the diverging walls 1 and 3, and 2 and 4, of the cooperating leg sections. The legs 9 and 9 of the clamps that terminate in the hooks are of such length that when the hooks engage the outer edges of the permanent sections, and the bolts 11 are applied to draw the clamp against the other legs, the clamps hold the two angle bars securely together, in manner that will be obvious.

15 By using two of the clamps C and C' opposite each other, as shown in Fig. 3, the cooperating derrick leg sections A and B are securely locked together apex to apex, and cannot move apart, or move relative to each other. The clamps themselves are held in position by a single bolt, which may be readily inserted and tightened up by a single operator with a wrench. The removal is equally simple, and the advantages of this structure 20 will be apparent to those familiar with the art.

As illustrated the holes for receiving bolts for attaching the clamps are provided in the reenforcing leg sections B. But they may be 30 provided in the angle sections A, and the clamps reversed, if desired. If the angle sections of the two legs are of different size the clamps will have one leg longer than the other, in proportion to the width of the respective angle bars, as will be readily understood.

I claim:

1. A clamp for attaching together parallel angle bars placed apex to apex with their legs 40 diverging, comprising an angle bracket member adapted to fit into the space between said diverging legs of the two angle bars and having a terminal hook on one end adapted to engage the edge of one leg of one angle bar, 45 the other end being adapted to be bolted to the adjacent leg of the other angle bar.

2. In a derrick construction comprising corner columns connected by girts and braces, the combination of two angle bar legs arranged apex to apex in parallel relation with adjoining sides diverging to form a column of the derrick, and a clamp adapted to fit into the space between diverging sides of the two legs, said clamp having a hook for engaging the edge of one of said diverging sides, and means to positively attach the clamp directly to the other of said diverging sides.

3. In a derrick construction comprising a permanent angle bar leg and a removable reenforcing angle bar leg positioned with their apices in juxtaposition and their sides respectively diverging, the combination of an angle bar clamp adapted to fit into the space between adjacent diverging sides of the two legs 60 having one side perforated and a hook on the

other side adapted to engage the edge of one of the angle legs, and a bolt attaching the other side of the clamp to the adjacent side of the other angle leg, whereby to clamp the reenforcing leg to the permanent leg.

4. A derrick construction comprising upright permanent angle bar legs with attached girts and braces for forming a tower, the apices of said angle bars being turned outward so that the sides of the angle lie in the planes of the sides of the tower, separate removable reenforcing legs for the derrick comprising angle bar sections joined at their ends and arranged with their apices placed in juxtaposition to the apices of the permanent leg members and their sides extending outward in diverging relation to the sides of the permanent legs, and clamps for holding the angle bars of the two legs in fixed relation to each other, said clamps comprising angle brackets adapted to fit into the angles between adjacent sides of the two derrick legs, one leg of the bracket having a hook adapted to engage an edge of one side of one leg and the other leg of the clamp being perforated, and a bolt attaching it to the adjacent side of the other derrick leg.

In testimony whereof, I sign my name.
JOSEPH P. FOUKES.
